(57) **CLAIM**

The ornamental design for a wireless microphone, as shown and described.

DESCRIPTION

FIG. 1 is a front, right and top perspective view of a first embodiment of a wireless microphone showing my design. FIG. 2 is a front, right, and top perspective view of a transmitter of the wireless microphone shown separately to show aspects of the design that are not visible when combined;

FIG. 3 is a rear, left, and bottom perspective view thereof; FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a front, right, and top perspective view of a receiver of the wireless microphone shown separately to show aspects of the design that are not visible when combined;

FIG. 11 is a rear, left, and bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a front, right, and top perspective view of a second embodiment of the wireless microphone;

FIG. 19 is a front, right, and top perspective view of a receiver of the wireless microphone shown separately to show aspects of the design that are not visible when combined;

(Continued)

FIG. 20 is a rear, left, and bottom perspective view thereof;
 FIG. 21 is a front elevation view thereof;
 FIG. 22 is a rear elevation view thereof;
 FIG. 23 is a left side elevation view thereof;
 FIG. 24 is a right side elevation view thereof;
 FIG. 25 is a top plan view thereof; and,
 FIG. 26 is a bottom plan view thereof.
 The broken lines shown in the drawings are included for the purpose of illustrating portions of the wireless microphone that form no part of the claimed design.
